UNITED STATES PATENT OFFICE.

PERCY HENRY DARNLEY, OF LONDON, ENGLAND, ASSIGNOR OF ONE-HALF TO BARNETT RICHARDS, OF LONDON, ENGLAND.

TYPEWRITER.

Application filed September 23, 1921. Serial No. 502,710.

To all whom it may concern:

Be it known that I, Percy Henry Darnley, a subject of His Majesty the King of England, and resident of London, in the 5 county of Middlesex and Kingdom of England, have invented certain new and useful Improvements in Typewriters, of which the following is a specification.

This invention relates to typewriters of 10 the kind comprising a rotatable member having a type-carrying flexible band disposed around the periphery thereof, the said member being adapted to be operated so as to permit the type to be moved selectively 15 into printing position.

According to this invention the rotatable member is operated by means of a lever adapted to be connected to the said member at different points thereof in accordance 20 with the type to be moved into printing position. The said lever may cooperate with a stop device when the selected type is in printing position, and the rotatable member may be provided with a flexible band 25 having studies in type for the purpose hereinafter referred to.

In order that the said invention may be clearly understood and readily carried into effect the same will now be more fully described by way of example with reference to the accompanying drawing, in which:—

Figure 1 is an elevation of a typewriter embodying the invention, the outer casing thereof being removed, the embodiment 35 shown being adapted for use more particularly in facilitating the learning of the letters of the alphabet by children and for spelling and such purposes.

Figure 2 is a plan view corresponding to 40 Figure 1.

Figure 3 is a similar view to Figure 2 but showing the outer casing in position, and

Figure 4 is a cross-section taken on the line $x-x$, Figure 2.

Referring to the drawing, a denotes the rotatable member and b the type characters disposed around the periphery thereof, the type characters in the example shown being formed integral with a rubber or other 50 flexible band c detachably connected to the said member a as by means of projections d on the latter engaging orifices in the band which may be further secured in position by means of wire d' (Figure 1) or the like 55 passed around it. The member a is rotat-

ably mounted with respect to a vertical shaft e secured at the upper end of an upwardly extending annular portion f (Figure 4) forming part of the base g of the apparatus. The said member a is adapted to be rotated by means of a handle h freely mounted on the shaft e and having an orifice h' adapted to engage with any one of an annular series of pins or projections i 60 on the upper face of the member a , the said handle being of a resilient character in order to permit of its being connected or disconnected from the member a in the manner aforesaid. Disposed in radial alignment with said projections i are letters corresponding to the capital letters of the alphabet, the type characters in the example shown denoting also the capital letters of the alphabet but having associated therewith 65 type representations the spelling of the names of which commence with the alphabetical letters as shown in Figure 1. The said member a is shown formed with openings j (Figures 2 and 4) at the upper face thereof whereby there are constituted radial arms merging into a central boss k and into an annular rim portion l on which the projections i are provided, the said openings being covered by a disc m detachably connected to the said arms and bearing the alphabetical letters in radial alignment with the said projections i . If desired, orifices or recesses may be provided in lieu of the said 70 projections i and the lever h may be provided with a projection in lieu of the orifice h' the said projection being adapted to engage selectively with the said orifices or recesses. Arranged concentrically with respect to the axis of the shaft e is an annular member n secured to the base 75 g and having an opening o therein through which the head p of a plunger device is adapted to be projected in order to co-operate with the band c and thereby obtain an impression of any type character or characters and/or representation or representations in alignment with the said opening o . In order to enable an impression to be obtained an upright extension q is provided on the base g the said extension having associated 80 with it a pad or plate r which may be provided with a portion r' embracing the said extension, the said plate being adjustably maintained in position by means of screws, 85 as shown, or by means of other appropriate 90

105

100

105

110

devices. The impression may be obtained for instance on a strip *s* (Figure 3) of paper or other suitable material interposed between the inner face of the pad *r* and preferably resilient and spaced fingers *t* attached at their lower ends to the said pad. As shown, the head *p* of the aforesaid plunger device is associated with an axially movable rod *u* freely mounted at diametrically opposite 10 site points on the annular portion *f* of the base *g* the said rod being bent downwardly to clear the annular member *n* and being extended outwardly between guides *u'* on the base *g* so as to terminate in a handle such as 15 the upright extension *v* for enabling the device to be manipulated manually against the action of a spring *w*. Rollers *y* to which ink is previously applied are provided for inking the type characters on the band *c* during 20 the rotation of the latter with the member *a*. The rollers *y* are shown connected to spring arms *z* adapted to maintain the said rollers yieldably against the type characters, or representations on the band carrying 25 the same. The said arms *z* are adjustably secured to upright extensions *g'* on the base portion *g*, one of the said extensions being projected so as to be disposed in the path of movement of the lever *h* and constitute 30 a stop *g''* therefor. The said stop is so disposed that in the event of the lever *h* being in contact therewith and the hole *h'* in the lever being engaged by one of the aforesaid pins or projections 35 *i*, a type character or characters and/or representation or representations corresponding to the alphabetical letter in radial alignment with the said engaged pin or projection *i* will be in register with the aforesaid opening *o*. An enclosing casing or cover *a'* secured to the base *g* is provided, the said casing having an opening *b'* at the upper end thereof to enable the member *a* to be rotated and the alphabetical letters 40 thereon to be exposed.

In the operation of the apparatus, assuming the strip *s* of paper or other suitable material is located at the printing point indicated in Figure 3 and the alphabetical letter "G" has been selected and the member *a* rotated until the handle *h* makes contact with the stop *g''* as shown in Figures 2 and 50 3, on actuating the rod *u* so that it is moved axially against the action of the spring *w* the head *p* associated with the said rod is projected through the opening *o* (Figure 4) and impinges on the resilient band *b* whereby by the type character G and a type representation denoting, in the example shown, a 55 goose (see Figure 1) which are then in register with the said opening *o*, are impressed on the said strip *s* which would be held during such action against the pad *r*. By selecting other alphabetical letters in the manner aforesaid, an impression of the corre-

sponding type characters and representations the spelling of the names of which latter commence with the selected letters, will be obtained. In the example shown on Figure 1, the type characters E, F, H and I have associated therewith type representations of an egg, a fish, a harp and an Indian, respectively.

It will be understood that other bands bearing more advanced studies in type (such for example as words spelt in full) may be substituted from time to time, in accordance with requirements.

It will also be understood that the apparatus may be adapted to print any suitable characters and/or representations, the printing of alphabetical characters and representations being only shown by way of example.

What I claim is:—

1. A typewriter comprising a circular rotatable member, printing elements carried by said member around the periphery thereof, a circular series of index elements on the said rotary member, a lever freely movable with respect to the rotary member and adapted to engage any one of the index elements whereby to actuate the rotary member and bring a printing element to printing position, and means for operating the printing element.

2. A typewriter comprising a base, a member rotatably mounted relatively to said base and having circularly spaced portions on the upper face thereof, a type-carrying flexible band disposed around the periphery of said member, a lever freely mounted with respect to the axis of said member and having a part thereof adapted to engage with the said circularly spaced portions to permit the type to be moved selectively into printing position, and a yieldable plunger device mounted on said base and adapted to act on said flexible band.

3. A typewriter comprising a base, a member rotatably mounted relatively to said base and having circularly spaced portions on the upper face thereof, a type-carrying flexible band disposed around the periphery of said member, a lever freely mounted with respect to the axis of said member and having a part thereof adapted to engage with the said circularly spaced portions to permit the type to be moved selectively into printing position, a stop device on said base with which said lever co-operates when the selected type is in printing position, and a yieldable plunger device mounted on said base and adapted to act on said flexible band.

4. A typewriter comprising a base, a member rotatably mounted relatively to said base and having circularly spaced projections on the upper face thereof, a type-carrying flexible band disposed around the periphery of

- said member, a lever freely mounted with respect to the axis of said member and having an orifice therein adapted to engage with the said projections to permit the type 5 to be moved selectively into printing position, a stop device on said base with which said lever co-operates when the selected type is in printing position, and a yieldable plunger device mounted on said base and adapted 10 to act on said flexible band.
5. A typewriter comprising a base, a member rotatably mounted relatively to said base and having circularly spaced portions on the upper face thereof, a type-carrying flexible band disposed around the periphery of 15 said member, a lever freely mounted with re-
- spect to the axis of said member and having a part thereof adapted to engage with the said circularly spaced portions to permit the type to be moved selectively into printing 20 position, a yieldable plunger device mounted on said base and adapted to act on said flexible band, yieldably mounted inking means carried by the said base and adapted to co-operate with said band, and an enclosing 25 casing adapted to be secured to said base and having an opening at the upper part thereof to permit rotation of the said rotatable member.
- I testimony whereof I have hereunto 30 signed my name.

PERCY HENRY DARNLEY.
